GIRDLE

Morris Bienenfeld, Brooklyn, N. Y.

Application July 3, 1937, Serial No. 151,786

1 Claim. (Cl. 2-27)

The present invention relates to ladies' foundation garments, and, more particularly, to girdles provided with an inner front portion for flattening the abdomen.

One object of the invention is to provide a belted girdle which is specially adapted for a figure which is of moderate size, but yet requires a girdle which is provided with means for flattening the abdomen. For this purpose the girdle is provided with an inner belt or front portion constructed and arranged to produce the desired flattening effect.

A further object of the invention is to provide a belted girdle having sections which are at least partially separable so as to facilitate the putting on and taking off of the girdle, and more particularly, to provide a belted girdle having separable sections connected together by a slide operated fastener such as a "zipper" and arranged so that the fastening of the belt in position draws the separable sections of the girdle together so that the movement of the "zipper" to closed position is facilitated.

A further object of the invention is to provide a girdle with a belted portion which has a two-way stretch, that is, a belt which is extensible both circumferentially and longitudinally of the wearer.

A yet further object of the invention is generally to improve the construction of belted girdles.

The above objects of the invention and other objects ancillary thereto will be fully understood from the following description considered with reference to the accompanying drawing forming a part of the present specification.

In the drawing:

Fig. 1 is a front view of the girdle illustrated in position on the wearer;

Fig. 2 is a rear view of the girdle;

Fig. 3 is an inside view of the front of the girdle;

Fig. 4 is an enlarged sectional view on the line 4-4 of Fig. 1.

Referring now more particularly to the drawing, the foundation garment here shown as a girdle 10, embodying the present invention, comprises sections secured together in body encircling relation. Said girdle includes a front panel 12 of suitable fabric which is preferably non-stretchable and inelastic, side sections 14 and 16 which are elastic transversely, or in a circumferential direction and substantially inelastic or of limited elasticity in a direction longitudinally of the wearer, and a rear panel 18 which is composed of suitable fabric which is non-stretchable and in-

elastic. The front panel 12 is provided with a lower elastic insert 20, and rear panel 18 is provided with an upper elastic insert 22. Said front and rear panels are also provided with stays 24 and 26, respectively, the front stays 24 being relatively short as indicated and the rear stays 26 extending substantially to the lower edge of the rear panel.

In accordance with the present invention, the front panel 12 and one of the side panels, here shown as the side panel 16, are separable for a portion of their length, that is, along a line extending from the upper edge 28 of the girdle to a point 30 located approximately two-thirds of the distance between said upper edge of the girdle and the lower edge 32 of the latter. For fastening said separable sections together a slide operated fastener 34 is provided. The usual stringers 36 and 38 of said fastener are attached at the adjacent edges of panel 12 and section 16. 20

In accordance with the present invention, the girdle is provided with a belt 40 comprising a central panel 42 composed of suitable fabric which is preferably non-stretchable and inelastic in a direction transversely of the wearer, but which is elastic in a direction longitudinally of the wearer as indicated by the arrow 44 in Fig. 3. Said belt also comprises side panels 46 and 48 stitched to central panel 42 and reinforced at the seams by strips or tapes 49. Said panels 46 and 48 are composed of suitable fabric which is elastic in a transverse direction as indicated by the arrows 50, but which preferably is non-stretchable and inelastic in a longitudinal direction. Central portion 42 is provided with reinforcing 35 cross strips 51 stitched thereto and to the vertical reinforcing strips 49. The upper edge of belt 40 is provided with an elastic tape 53 and the lower edge of said belt portion is provided with a similar elastic tape 55, said tapes 53 and 40 55 being stretchable in a direction longitudinally thereof.

Belt 40 is attached to the girdle at the inner side of front panel 12 by stitching the side edge of one side panel, here shown as panel 46, by the 45 seam 52 by which the side panel 14 is attached to the front panel 12 at one side thereof. The opposite side edge of portion 40 is provided with an inelastic fabric strip 54 carrying hooks 56 for engagement with eyes 58 carried by an inelastic 50 fabric strip 60. Said strip 60 is stitched to an inelastic fabric flap 62 which is stitched to panel 16 adjacent the separable side edge thereof by a line of stitching 64 which also passes through the fastener stringer 38. Elastic garter tabs 66 are 55

attached at their ends to the bottom of belt portion 40 and to the bottom edge of front panel 12, respectively. Garter tabs 69 are stitched to the lower edge of rear panel 18.

- 5 It will be observed that when the wearer adjusts the girdle on her body, before the fastener 34 is closed, the hooks on the belt are engaged with the eyes on strip 60 which is attached to flap 62. In this manner the front panel 12 and the side panel 16 are drawn together and disposed with their edges close to each other so that the slider 35 of the slide fastener 34 may be operated with minimum resistance to effect the closure of the slide fastener. By virtue of this arrangement 15 the necessity for two rows of hooks and two rows of eyes is eliminated as the same set of hooks and eyes which are used for fastening the belt portion of the girdle in position also brings the separable girdle portions close together for relieving the strain on the slide operated fastener. Flap 62 is of suitable thickness and is preferably 20 soft and padlike in order to prevent the hooks and eyes from causing any discomfort to the wearer.
- 25 Thus it is seen that the girdle herein shown and described as the preferred embodiment of the invention is well adapted to accomplish the several objects of the latter. It will be understood, however, that the invention may be embodied 30 otherwise than as here shown and that in the embodiment illustrated herein certain changes in the construction and arrangement of parts

may be made. Thus, for example, while I have described the central portion 42 of belt 40 as elastic, which is a preferred feature of the invention, said section may be composed of inelastic fabric, although it is preferred that the side sections 5 46 and 48 have elasticity in a transverse direction as above described. Accordingly, in view of the changes which may be made in the construction herein shown, I do not wish to be limited precisely thereto, except as may be required by the appended claim considered with reference to the prior art.

Having thus described my invention, what I claim and desire to secure by Letters Patent is:

A foundation garment such as a girdle having 15 a belt on the inside thereof in position to overlie the wearer's abdomen, said belt comprising a central portion which is elastic longitudinally and inelastic transversely, and side portions which are elastic transversely, one of said side portions 20 being attached at its outer edge to the girdle, said side portions permitting the belt to be stretched and thereby tensioned when in position on the wearer, separable fasteners on said girdle and on the outer edge of said other side portion for 25 releasably fastening the belt in said position, said girdle having separable portions adjacent said other side edge of the belt in the fastened position of the latter, and a slide operated fastener for releasably securing said separable portions 30 together.

MORRIS BIENENFELD.
